1

The present invention relates to magnetostriuctive devices and in particular to those of the type comprising a bar made from magnetostriuctive material mounted at a vibration node and longitudinally oscillating, the bar being supported intermediate its ends by a bearing and a coil surrounding the bar on each side of the bearing. The bar is premagnetized by one or more permanent magnets and the terminal ends of the two coils (four in number) form what is commonly known as a "four-pole."

Such four-poles have various uses such for example as wave filters or as frequency stabilizers, and are described in detail in various patents such as Swiss Patent No. 197,694 and United States Patent No. 1,750,124.

The mounting of the bar, as experience has shown, causes difficulties because two contradictory requirements must be met. On the one hand, the bar mounting should allow the bar full freedom of movement in the longitudinal direction, also for mounting at a node, this being necessary in consideration of the practically never perfect immobility of the node in the bar. On the other hand, however, the bar must be secured crosswise to the longitudinal axis as fixedly as possible in order that existing air gaps between the magnetostriective bar and the one or more premagnetizing permanent magnets and also any air gaps provided in the flux return yokes will remain unchanged while the bar is oscillating. Moreover, also the coils energizing the bar should be capable of being wound as close to the bar as possible without touching the same, and this again requires an accurate and laterally fixed mounting of the bar. In addition, the entire four-pole should form a structural unit which as a whole is easily exchangeable and is sturdy enough to be capable of being used in portable equipment.

The two extreme requirements concerning the mounting of the bar can be fulfilled according to the present invention by providing a circular disc on the bar at the node where it is to be mounted and clamping the disc itself at its rim portion to a support. The bar is thereby mounted crosswise to the longitudinal axis with sufficient resistance to lateral displacements. The disc should be proportioned with respect to thickness and diameter in a manner such that one of its inherent frequencies coincides with the inherent frequency of the bar with which the bar is magnetostriactively energized. For example, the bar may be allowed to operate in its fundamental frequency (one node in the center of the bar),

dimensioning the disc in such a way that also the fundamental frequency of the disc coincides with the fundamental frequency of the bar. However, as a working frequency for the disc there may be selected for example the frequency of its third harmonic and as a working frequency for the bar for example the frequency of its fifth harmonic, and it is then merely necessary to fulfill the condition that the working frequencies of the disc and bar coincide.

All of the conditions mentioned can be fulfilled by the present invention, namely in that a circular disc, whose working frequency in the case of rigid insertion of the disc rim corresponds to the working frequency of the longitudinally oscillating bar, serves as a bearing for the oscillating bar, in that this bearing disc is provided in the center of the bar concentrically thereon, and that there are connected with the rim portion of the bearing disc three non-magnetizable bolts which extend on both sides of the bearing disc parallel with the oscillating bar, in such a way that the centers of the three bolts form the edges of a prism having the cross section of an equilateral triangle, the longitudinal axis of the prism and of the oscillating bar coinciding, and that at the free ends of the three bolts there is provided on both sides of the bearing disc and parallel with this disc an end plate for each, there being installed between each end plate and the bearing disc one of the said coils concentrically with the oscillating bar and there being inserted on both sides of the bearing disc at least in one of the three spaces between each pair of adjacent bolts a cylindrical permanent magnet parallel with the oscillating bar and there being installed in at least one of the remaining free spaces a magnetizable bar which serves as regulable shunt yoke for the magnetic flux between the bearing disc and the end yokes.

In the drawings which illustrate alternative embodiments of the invention:

Fig. 1 is a vertical central section taken on line 1—1 of Fig. 2 showing a construction adapted particularly for use with frequencies below 50 kilocycles;

Fig. 2 is a horizontal section on line 2—2 of Fig. 1;

Figs. 3 and 4a—4d are curves showing various performance characteristics of the vibrator;

Fig. 5 is a vertical central section of a somewhat different construction adapted particularly for use with frequencies between 50 and 500 kilocycles; and

Fig. 6 is a vertical view partly in section illustrating another modified construction.

With reference to Figs. 1 and 2 in particular, the magnetostrictive four-pole is seen to be comprised of a straight cylindrical bar 1 of magnetostrictive material, the composition of which is discussed hereinafter. Intermediate the ends of bar 1 and around the same is positioned a circular bearing disc 2 of magnetizable material, the bar and disc being concentric, and the central hole in the disc through which the bar passes being of substantially the same diameter as the bar to provide a tight press fit therebetween. Three bolts 3 of a non-magnetizable material such as for example brass, are rigidly connected with the rim portion of disc 2 which is preferably reinforced by annular discs 4, 4' applied to opposite faces thereof and held in position by the bolts 3 each of which as illustrated is divided into two halves secured together with the reinforcing discs 4, 4' and disc 2 secured therebetween.

As is evident from Fig. 2, the centers of the three bolts 3 form the edges of a prism which presents in transverse section the form of an equilateral triangle through the center of which passes the axis of bar 1 which extends parallel to the bolts 3.

The upper and lower ends of the three bolts 3 terminate in threaded sections 14 secured by nuts 14' to end plates 5, and the latter are provided with axial apertures through which the bar 1 passes. The apertures in the plates 5 are preferably of substantially the same diameter as that of bar 1 so as to provide a path of low reluctance for the magnetic flux produced in the bar 1 to pass into the plates 5. Some radial clearance between bar 1 and end plates 5 is however necessary.

For energizing bar 1 magnetically, two coils 6 are utilized. Each coil is carried on a spool 7 arranged concentrically on the bar and one of the coils is arranged below and the other above the centrally located disc 2.

Extending between central disc 2 and each of the end plates 5 is a permanent magnet in the form of a cylindrical bar. The magnet bars 8, 8' have their outer ends secured to plates 5 by screws 9, are arranged coaxially and parallel with the bar 1 of magnetostrictive material, and are disposed in any one of the three spaces between any two adjacent bolts 3. In the two remaining spaces between the bolts 3, are arranged cylindrical bars 10 of magnetizable material. Bars 10 which extend parallel to bars 1 and 8, 8' are secured rigidly at their inner ends to the reinforcing discs 4, 4' and their outer ends terminate short of the end plates 5 to establish air gaps 12 the lengths of which can be made adjustable by screws 11 axially aligned with the bars 10 and which thread through the plates 5. The bars 10 and screws 11 thus constitute a shunt yoke for regulation of the premagnetization of bar 1 from the permanent magnets 8, 8'. If desired, to increase the premagnetizing effect of bar 1, a second set of permanent magnet bars 8, 8' may be used in place of one of the sets of magnetizable bars 10.

The component assembly as described is preferably enclosed by a cup-shaped casing 13 to make it dust proof, the casing being divided axially into two halves which fit into a centrally located ring 15. The threaded ends 14 of bolts 3 extend through the end walls of the casing halves and are anchored there by nuts 14'' which when tightened press the halves of the casing towards

each other into the ring 15. Ring 15 also serves to support the connecting terminals 16 for the coils 6.

The electrical properties of the magnetostrictive four pole shown in Fig. 1 are as follows.

If to one of the two coils 6 there is connected an alternating voltage of constant maximum amplitude whose frequency of alternation is variable between f_1 and f_2 , a voltage is obtained at the terminals of the other coil 6 having a variation dependent upon the said frequency and which varies according to the curve U shown in Fig. 3. The frequency f_0 corresponds to the frequency to which both the bar 1 and bearing disc 2 are tuned, the working frequency corresponding in the present example to the frequency of fundamental vibration both of bar 1 and disc 2.

From the curve in Fig. 3, the Q factor of the four pole can be determined according to the equation

$$Q = \frac{f_0}{\Delta f}$$

f being measured between the voltage values which amount to

$$\frac{1}{\sqrt{2}}$$

times the maximum voltage value. With the construction shown in Fig. 1, Q factors of 10,000 and more have been attained.

With reference to the curves in Figs. 4a-4d, there are shown, respectively, the qualitative variation of the premagnetization induction B, the Q factor, the resonance voltage transmission U and the inherent frequency displacement

$$\frac{\Delta f}{f_0}$$

as a result of the ΔE effect discussed below, all curves being plotted as a function of the change in premagnetization field strength H. Dependent upon the selection of H therefore, the four pole presents different properties. In zone I (up to the broken vertical boundary line of premagnetization field strength value H) the Q factor is relatively high, the voltage U is relatively low, and the factor

$$\frac{\Delta f}{f_0}$$

is relatively high. The possibility of compensation by the ΔE effect lies in the order of magnitude 10^{-3} . In zone II (to the right of the broken vertical line value of premagnetization field strength H) the Q factor is somewhat lower but the voltage transmission U is increased and factor

$$\frac{\Delta f}{f_0}$$

is smaller for a given change in frequency of the field variations.

Since for given dimensions the disc 2 and bar 1 possess a certain working frequency, means must be provided to tune the finished four-pole accurately to a desired theoretical frequency. For this purpose the property of ferro-magnetic materials known as ΔE effect can be utilized. The modulus of elasticity as a function of the premagnetization is, in fact, not a constant, and therefore, by varying the premagnetization of bar 1 the modulus of elasticity thereof and hence its inherent natural frequency of vibration can be varied within narrow limits. The premagnetization from magnets 8, 8' can be varied by

an air gap in the circuit of the premagnetization flux. For this purpose there serves the air gap adjustable with the aid of the screw 11 in the shunt yoke 10 as previously explained.

If desired, the premagnetization of the magnetic circuit by the permanent magnets can be made adjustable by providing an adjustable air gap between one end of the magnet 8a and an adjustable screw 13a threaded into the end plate 5a, as shown in Fig. 6, the opposite end of magnet 8a being secured to the annular disc 4a.

Depending on the desired intensity of the premagnetization of bar 1 it is possible to replace the yokes 10 by permanent magnets. Thus one, two, or three permanent magnets can be installed 15 in the arrangement on each side of the bearing disk between the bolts 3 as previously explained.

Since the frequency constants of the four-pole when used as wave filter or as vibration stabilizer must be as great as possible also in the case of temperature fluctuations, certain requirements must be observed in selecting the material of the bar 1. For the bar 1 a material should be selected whose temperature coefficient of its modulus of elasticity is at least equal to its temperature coefficient of linear expansion but with opposite sign, i. e. one coefficient is negative and the other positive. Under such conditions the change in frequency of the magnetostrictively energized bar per degree change in temperature will be practically zero. Experiments with a bar of Elinvar (an alloy of about 49% Fe, 36% Ni, 12% Cr, .5% Si, 1% C) have shown that after suitable thermal treatment (annealing to about 850 deg. C.) a frequency variation of less than 1×10^{-6} cycles per degree is obtainable.

As can be seen from Fig. 1, the bar 1 must not shift crosswise to its longitudinal axis, as this may easily cause disturbances in the vibration as soon as the bar touches the spools 7 or the end plates 5 anywhere. If one selects for the disc 2 a material whose coefficient of expansion is smaller than that of the material of the bar 1 (e. g. Invar, an alloy of 36% Ni and 64% Fe) and if one presses the disc onto the bar at a temperature below the mean operating temperature, one obtains at the operating temperature an insertion which is sufficiently rigid and stable to prevent cross displacements of the bar 1.

The embodiment of the invention shown in Figs. 1 and 2 can be used for frequencies in the range below 50 kilocycles. For frequencies between 50 and 500 kilocycles the embodiment according to Fig. 5 is especially suitable. In accordance with the higher working frequencies and the consequent shorter dimensions of the bar 1', also the bearing disc 2' should be proportionally thinner. In order to be able to make the edge of this disc rigid nevertheless, it is advisable to provide the disc not with the clamping discs 4 shown in Fig. 1, but rather with a thickened rim 2a. In this rim the bolts 3 may be fastened and formed as in Fig. 1. However, a construction as per Fig. 5 may also be used, consisting of an inner bolt 20 with sleeves 21 thereon. In a central bore in the upper and lower end plates 5' a set screw 22 is provided whose axis points in the direction of the longitudinal axis of the oscillating bar 1' and is separated from the end face thereof by the air gap 23. This arrangement has two advantages. First, the space between each end plate 5' and disc 2' can be made sufficiently long to install the coil body (not shown) even if the bar 1' is short (that is, if the frequencies are high). Second, the set screws 22 permit a fine regulation

of the inherent natural frequency of the bar 1' even when it is desired to press the permanent magnets 8'' and bars 10' simply between the end plates 5' and the disc 2', omitting the set screws 9 and 11 of Fig. 1.

In Fig. 5, however, a casing 13' is shown (partially broken away) which is pressed in a base plate 24 so as to be dust-proof, this base plate supporting at the same time the four connection terminals 25 for the coils, thus being designed like the multi-pronged base of a conventional vacuum tube.

Instead of tuning the bar 1 and the disc 2 with each other on their fundamental frequency, other combinations are of course also possible, for example, the fundamental frequency of the plate 2 can be tuned on the frequency of a harmonic (for instance the third or the fifth), this being advisable when it is desired to work with such high frequencies that a bar working at the fundamental frequency would be too short to be handled conveniently. A more detailed discussion of tuning the plate and bars can be found in the literature available on this subject such as Hütte's 25 "Des Ingenieurs Taschenbuch."

In conclusion, it is to be understood that while the foregoing illustrated embodiments of the invention are to be preferred, various changes in the construction and arrangement of component parts may be devised by those skilled in the art without however departing from the spirit and scope of the invention as defined in the appended claims.

I claim:

- 35 1. A magnetostrictive four-pole comprising a bar of magnetostrictive material, a circular bearing disc of magnetizable material mounted concentrically upon and rigidly connected with said bar intermediate the bar ends, the working frequency of said mounted disc corresponding to the working frequency of the longitudinally oscillatable bar, three bolts of non-magnetizable material extending from the rim portion of said disc in opposite directions parallel with said bar, said bolts being so spaced about the axis of said disc as to form the edges of a prism having the cross section of an equilateral triangle and whose axis coincides with the axis of said bar, end plates of magnetic material parallel with said bearing disc and secured to the opposite ends of said three bolts, cylindrical coils concentric with and surrounding said bar respectively between said bearing disc and said end plates, a permanent bar magnet arranged longitudinally of said magnetostrictive bar between said bearing disc and each of said end plates in one of the three spaces between each pair of said bolts, and at least one bar of magnetizable material arranged longitudinally of said magnetostrictive bar between said bearing disc and each of said end plates in one of the two remaining spaces between each pair of said bolts, said last bars functioning as a shunt for the magnetic flux which flows in said magnetostrictive bar.
- 40 2. A magnetostrictive device as defined in claim 1 wherein said bearing disc is provided with annular members secured to opposite faces thereof at the rim portion to reinforce the same.
- 45 3. A magnetostrictive device as defined in claim 1 wherein said bearing disc has a thickened rim portion to reinforce the same.
- 50 4. A magnetostrictive device as defined in claim 1 wherein said three bolts each consist of
- 55 two halves joined together in end to end relation
- 60
- 65
- 70
- 75

at said bearing disc with the latter clamped therebetween.

5. A magnetostrictive device as defined in claim 1 wherein said three bolts each are continuous between said end plates passing through apertures in said bearing disc and which further include a sleeve surrounding each bolt between the bearing disc and end plates, said bearing disc being clamped between the two sleeves of each bolt.

6. A magnetostrictive device as defined in claim 1 wherein the ends of said magnetostrictive bar pass at least partially through axial apertures in said end plates.

7. A magnetostrictive device as defined in claim 1 wherein the ends of said magnetostrictive bar terminate short of said end plates and wherein each said end plate is provided with an axially disposed screw adjustable longitudinally and confronting the end faces of said magnetizable bar to establish an adjustable air gap therebetween.

8. A magnetostrictive device as defined in claim 1 wherein the said magnetizable bars constituting said flux shunt are each secured at one end to said bearing disc, the other end thereof terminating short of the associated end plate, and screws adjustable longitudinally in said end plates and confronting the end faces of said magnetizable bars to establish adjustable air gaps therebetween.

9. A magnetostrictive device as defined in claim 1 wherein said bar magnets are clamped between the rim portion of said bearing disc and the associated end plate.

10. A magnetostrictive device as defined in claim 1 wherein said bar magnets are each secured at one end thereof to said bearing disc, the other end thereof terminating short of the associated end plate, and screws adjustable longitudinally in said end plates and confronting the end faces of said bar magnets to establish adjustable air gaps therebetween.

11. A magnetostrictive device as defined in claim 1 and which further includes a two-part cup-shaped casing therefor, the two casing halves being connected by a ring surrounding said bearing disc.

12. A magnetostrictive device as defined in claim 11 wherein said ring supports the electrical terminals connected to the four terminal ends of the said two coils.

13. A magnetostrictive device as defined in claim 1 and which further includes a cup-shaped casing therefor having a base plate at one end supporting the electrical terminals connected to the four terminal ends of the said two coils.

HEINZ BLOCH.
